RADIO RECEIVER

Shirley Irving Weiss, New York, N. Y.

Application October 11, 1945, Serial No. 621,745

12 Claims. (Cl. 250—14)

1

The present invention is concerned with radio receivers of novel and striking appearance, that lend themselves for use in the home, but more especially for any of a variety of displays for commercial and advertising purposes.

An object of the invention is to provide a radio receiver of the above type, which is of relatively simple and compact construction that is easy to service, and which has none of the external characteristic appearance of a radio but simulates a unit for an entirely different purpose that gives little or no indication of its utility as a radio receiver.

Another object is to incorporate all of the functional radio receiver elements in a single sub-assembly that readily admits of being mounted into a casing of odd shape to which the sub-assembly is conformed, and which in use distributes the sound in all directions with superior sound effects.

In the accompanying drawings in which is shown one of various possible embodiments of the several features of the invention,

Fig. 1 is a view in longitudinal cross section, taken on line 1—1 of Fig. 3,

Fig. 2 is a transverse sectional view taken on line 2—2 of Fig. 1,

Fig. 3 is a transverse sectional view taken on line 3—3 of Fig. 1,

Fig. 4 is a transverse sectional view taken on line 4—4 of Fig. 1, and

Fig. 5 is a perspective view showing the general appearance of one embodiment of the unit.

Referring now to the drawings, the radio receiver unit comprises a hollow base 10 which may be generally rectangular, as shown, with rounded corners, but may if desired be circular, hexagonal, octagonal or of any other plan area. The base has ports 12 for the electrical leads and other openings, such as slits 11, for emission of the sound and distribution thereof in all directions. The upper wall 13 of the base has a bezel 14, rigid therewith which rises therefrom. Said upper wall is illustratively shown with a concavely upward cylindrical upper face, so that the rising bezel wall which is level at its upper edge is of non-uniform height that conforms to such concavity.

Mounted in the bezel 14 is the lower open edge of the casing 15, which fits snugly in the bezel and is preferably cemented therein. The bezel and the lower casing rim therein may be of any polygonal face area, regular or irregular, but these parts are ordinarily circular, as shown.

Within the casing and applied thereto through the open bottom is the functional radio receiver structure or chassis which is preferably a complete, unitary sub-assembly. In a preferred embodiment that sub-assembly comprises a conventional loud speaker structure S, the diaphragm 16 of which is mounted in its case 17 to which is affixed the operating magnet 18. The loud speaker faces downward, as shown to be disposed substantially at the bezel, as shown and described below. Affixed to the frame 19 of the loud speaker is an upstanding panel 20 which desirably is rectangular and of thin stock and may be laterally flanged as at 21. This panel serves as the support for all of the fixed or non-adjustable equipment of the radio receiver. The panel mounts the various radio tubes 22 in sockets 23 affixed to the front panel face and with their axes at right angles to the panel. Desirably the panel is mounted in a plane well to one side of the cylindrical casing, as best shown in Fig. 2, so as to afford ample room within a relatively small casing for the entire height of the radio tubes and their sockets.

25 The various fixed condensers, resistors and the like, which are circuit determining elements of the conventional radio receiver circuit, are desirably mounted on the rear face of the panel and readily accommodated in the small segmental space between said rear face and the casing, as shown; the axes of said various elements being parallel or nearly parallel to the plane of the panel.

30 The variable or adjustable elements of the radio receiver are preferably affixed with respect to the panel and extend thereabove, as shown. In one simple and desirable embodiment, these adjustable elements include a variable tuning condenser C and a volume control resistor member V, the latter preferably above the former. In a desirable embodiment, the frame 24 of the variable condenser is affixed directly to a horizontal flange 25 on the upper edge of the panel. 35 The volume control member V is mounted coaxially with shaft 26 of the condenser, preferably by depending from the upper arm 28 of a U-shaped bracket 27, to which it is affixed by nut 30, the lower arm 28 of the bracket being affixed to the frame 24 of the condenser. For effecting the tuning and volume control, operating shafts rise from the condenser and the volume control member. To this end the volume control member V has a shaft extension 31 rising therefrom. The operating shaft 26 of the condenser has the lower

arm 32 of a yoke 33 affixed thereto, which yoke straddles the volume control member V and which has an upper arm 34 affixed to an operating sleeve 35 coaxially with and encompassing the shaft 31.

As shown, the volume control member V and the extension shaft 31 thereof, occupy a considerably smaller diameter than the panel 20, the parts mounted thereon and the variable condenser C thereabove. Therefore, it is feasible and preferable to reduce the upper part of the cylindrical casing to a frusto-conical section 36 about the volume control member V, and a generally cylindrical, preferably inwardly tapering, neck 37 about the operating shaft extensions 31 and 35. A pilot light 38 may conveniently be mounted on top of the condenser frame 24 and laterally of bracket 27.

It will be clear that the entire assembly as thus far described, may be introduced upwardly through the hollow base 10 into the cylindrical casing 15. The assembly is mounted in position, desirably by a cross strap 39 diametrically across the mouth of the loud speaker S and affixed thereto as by bolts 40, said strap having outward ends that may be affixed as by screws 41 to the inner periphery of the bezel 14 and, if desired, further screws 42 may clamp the outward extremities 43 of the strap to the lower rim of the bezel 14. Accordingly, the unitary structure described is securely mounted in the casing.

The operating knobs preferably include a lower knob 44 which may have a skirt 45 telescoped over the reduced upper rim 46 of the casing 15. That knob is affixed to the hollow operating shaft 35 by means of a set screw 47 depressed within a radial bore 48 in the knob. The inner shaft 31 has preferably an enlarged head or button 49 retained in place, as shown above the knob 44, at the top of the unit.

It will be seen that the receiver is readily tuned by rotation of the knob 44 at the upper end of the casing, which knob if desired may have appropriate scale markings (not shown), and the volume is controlled by turning the upper button 49.

In performance, the arrangement of the loud speaker diaphragm in a horizontal plane facing downward and the distribution of ports 11 thereabout and especially at the slits 11 in the top of the base, makes for a better distribution of sound laterally of the receiver in all directions than does the conventional small receiver in which the loud speaker faces forwardly for emission through the front panel. Moreover, by the arrangement set forth, the table or other support upon which the unit rests, may contribute markedly to the quality of output, depending on its sound reflecting or sound absorbing characteristics, to act for any of the wide variety of sound-board effects.

It will be obvious that the casing may be made in any of numerous shapes. One desirable shape illustratively shown simulates a bottle, the tuning control knob 44 simulating the decorative trim of the bottle neck and the volume control button 49 at the top simulating the rim of the stopper. In such application the invention lends itself readily, in addition to the primary function of a radio receiver, for use as an effective advertising medium for packaged goods, such as whiskey, beer or the like, for display in taverns and retail stores. Obviously the unit could be displayed in any of a variety of other casings simulating any

of a wide variety of container or other structures.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A radio receiver, comprising a relatively flat base having an open interior and ports through the wall thereof, said base having a bezel on the upper surface thereof, a casing open at its bottom affixed in said bezel and rising therefrom, a receiver assembly adapted to be introduced through the bottom of said base into said casing, said assembly including a downwardly facing loud speaker structure, a panel affixed thereto and rising therefrom, various radio tubes and fixed circuit determining elements affixed to said panel, variable control elements affixed to said panel and rising therefrom, said control elements having coaxial operating shafts and including a variable condenser and a volume control member, means affixing the lower end of said 30 loud speaker structure to said base, and concentric operating knobs secured to the upper end of the respective shafts and accessible from the top of the casing for effecting adjustment of the variable circuit controls.
2. The combination recited in claim 1, in which a transverse strap affixed to the lower end of the loud speaker structure straddles the bezel and is removably affixed thereto.
3. The combination recited in claim 1, in which 40 the operating knobs are removable with respect to the upper ends of the coaxial shafts and the lower of said knobs extends directly over the upper end of the casing.
4. A radio receiver, comprising a hollow base 45 having sound emitting ports through the wall thereof, a circular bezel on the upper wall of said base, a generally cylindrical casing open at its bottom and affixed at its lower edge to said bezel, a radio receiver assembly enclosed in said casing, 50 said receiver assembly including a downwardly facing loud speaker unit at the lower end thereof, a panel affixed to said unit and rising therefrom, various tubes and fixed circuit determining elements affixed to said panel, variable circuit control elements rising from said panel, one above the other, having frames affixed to said panel, and coaxial operating shafts, said shafts having operating extensions rising from said variable control elements, one encompassed by the other, 55 and a pair of coaxial operating knobs affixed to the respective shaft extensions, said knobs being at the uppermost part of the casing.
5. The combination recited in claim 4, in which the variable circuit control elements include a 60 variable condenser directly above the panel, and a volume-control unit directly above the condenser, the inner shaft extension being connected to said volume-control unit, and the encompassing shaft extension having a yoke with one arm affixed to the lower part thereof, straddling the volume-control element and with its other arm affixed to the shaft of the variable condenser.

6. A radio receiver comprising a hollow supporting base having ports through the wall thereof for sound emission, a circular bezel on the

upper face of said base, a generally cylindrical casing open at its lower edge and affixed thereto in said bezel, said casing being constricted to a narrow neck near the upper end thereof, a radio receiver assembly affixed with respect to said base and rising therefrom through said neck, said assembly including a downwardly facing loud speaker structure, an upright panel affixed thereto near the lower end thereof, various tubes and fixed circuit determining elements affixed at opposite sides of said panel, a variable condenser having a frame affixed to said panel and a vertical shaft, a volume-control member having a shaft coaxial with that of said condenser, a yoke affixed at one arm to the shaft of said condenser, straddling said volume-control member and having affixed to the other arm thereof a hollow condenser operating shaft rising therefrom, a solid operating shaft for said volume control member extending through said hollow shaft, the upper ends of both of said shafts being in the vicinity of the top of said casing, an operating knob affixed to said hollow shaft, and an operating button coaxial therewith, affixed to said solid shaft, and mounting means removably attached to the said bezel and the loud speaker structure.

7. The combination recited in claim 6, in which said mounting means comprises a transversely extending strap.

8. The combination recited in claim 6, in which the upright panel is at a substantial distance from the axis of the cylindrical casing, the tubes extending from the front of the panel at right angles thereto within the casing and the fixed condensers are mounted on the rear of the panel with their axes substantially parallel to the panel.

9. The combination recited in claim 6, in which the volume control member depends from the upper arm of a U-shaped bracket, the lower arm of which is mounted on the condenser frame.

10. A radio receiver unit in the form of an advertising novelty simulating a bottle on a base, said unit comprising a hollow base with ports through the wall thereof for sound emission, said bottle structure being open at its lower end, said base having a bezel supporting the lower edge of the bottle structure, a radio receiver sub-assembly comprising a downwardly facing loud speaker structure, an upstanding panel affixed thereto and rising therefrom, said panel being at a substantial distance from the axis of the bottle structure, radio tubes removably affixed to and extending at right angles to one face of said panel, fixed condensers affixed to said panel at the opposite face thereof, variable circuit control

elements, including a variable condenser and a volume-control member, one above the other, rising from the panel and supported thereon, coaxial operating shafts for said condenser and said volume-control member and rising through the neck of said bottle structure, a strap diametrically across the loud speaker and across the bezel and removably affixed to the latter to sustain the radio-received assembly within the bottle structure, an operating knob for one of the variable elements affixed to one of the operating shafts and simulating the bottle neck trim, said knob being telescoped at its outer edge over the rim of the bottle, and an operating button above said knob simulating a bottle stopper and affixed to the other shaft of said unit.

11. The combination recited in claim 10, in which the volume-control member extends above the variable condenser, the former has a solid operating shaft rising therefrom, the condenser has a hollow operating shaft encompassing said solid shaft, said hollow shaft being connected to the condenser by a yoke straddling the volume-control member.

12. A radio receiver assembly comprising a downwardly facing loud speaker having a frame, an upright panel affixed to said frame having tube sockets at the forward face thereof and fixed circuit-determining elements mounted on the rear face thereof, a variable condenser rising from the upper edge of said panel and having an upright shaft, an upright U-shaped bracket affixed to the frame of said condenser, a volume-control member depending from the upper arm of said bracket and having a shaft coaxial with that of said condenser, said volume-control member having a shaft rising therefrom, and a yoke having its lower arm connected to said condenser shaft, straddling said volume-control member and having a hollow shaft rising therefrom encompassing the volume-control shaft.
